CLAIM

The ornamental design for a footwear, as shown and described.

DESCRIPTION

FIG. 1 is a front, top, and left side perspective view of an embodiment of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a back, bottom, and right side perspective view thereof.

The broken lines in the drawings show portions that form no part of the claimed design.

1 Claim, 7 Drawing Sheets
